[57] CLAIM

The ornamental design for an apparatus for linearly displacing a rotatable spindle, as shown and described.

DESCRIPTION

FIG. 1 is a perspective view of an apparatus for linearly displacing a rotatable spindle, showing our new design;

FIG. 2 is a front elevational view of the apparatus for linearly displacing a rotatable spindle of FIG. 1;

FIG. 3 is a rear elevational view of the apparatus for linearly displacing a rotatable spindle of FIG. 1;

FIG. 4 is a left side elevational view of the apparatus for linearly displacing a rotatable spindle of FIG. 1;

FIG. 5 is a right side elevational view of the apparatus for linearly displacing a rotatable spindle of FIG. 1;

FIG. 6 is a top view of the apparatus for linearly displacing a rotatable spindle of FIG. 1; and,

FIG. 7 is a bottom view of the apparatus for linearly displacing a rotatable spindle of FIG. 1.

The broken line showing of a drill press is for illustrative purposes only and forms no part of the claimed design.
